(57) **CLAIM**

The ornamental design for a display screen or portion thereof with an animated graphical user interface, as shown and described.

DESCRIPTION

FIG. 1 is a first image of a sequence of a display screen or portion thereof with an animated graphical user interface. FIG. 2 is a second image thereof.

FIG. 3 is a third image thereof; and,
FIG. 4 is a fourth image thereof.

The portions of the figure shown in broken lines do not form part of the claimed design. Grey portions in the drawings illustrate contrast.

1 Claim, 4 Drawing Sheets
